APPARATUS FOR TESTING EXTERNAL THREADS ON VALVE STEMS

Leland R. Adams, Akron, Ohio, assignor to The Firestone Steel Products Company, Akron, Ohio, a corporation of Ohio

Application May 16, 1930. Serial No. 453,066

13 Claims. (Cl. 33—199)

This invention relates to apparatus for testing the external thread on valve stems.

The general object of the invention is to provide efficient, inexpensive, foolproof means for rapidly and accurately testing the quality and length of the external thread on small objects such as valve stems.

A more particular object of the invention is the provision of a rotatable nut or internally threaded bushing which is automatically reversed after screwing down upon the valve stem a determined adjustable distance.

The above and other objects of the invention are achieved by the apparatus illustrated in the accompanying drawings and described below, it being understood that the invention is not limited to the exact details thereof shown and described.

In the drawings:

Figure 1 is a front elevation of the apparatus embodying the invention;

Figure 2 is a side elevation thereof;

Figure 3 is a horizontal sectional view taken on line 3—3 of Figure 1;

Figure 4 is the wiring diagram of the apparatus.

The apparatus comprises a frame 5 being formed with a base 6 and a bracket 7. Extending between the base 6 and the bracket 7 are channels 8—8 which slidably carry a cross bar 9. The center of the cross bar 9 is enlarged as at 10 which enlargement is grooved as at 13 to receive the head 14 of a valve stem 15. Plates 16 secured to the enlargement 10 and extending over the groove 13 prevent relative longitudinal movement of the valve stem and the cross bar 9. In order to prevent rotary movement of the valve stem small plates 17 which bear against the flats of the valve stem are secured to the plates 16.

Axially aligned with the valve stem 15 is a hollow spindle 18 journalled in the bracket 7 and which is secured to the shaft 19 of a motor 20 mounted on the upper end of the frame 5. Removably secured to the end of the hollow spindle 18 is a nut or an internally threaded bushing 23 which is adapted to cooperate with and test the external threads on the valve stem as hereinafter described.

The switches for controlling the operation of the motor 20 include a switch 24 mounted on the base 6. The switch 24 may comprise a pair of contact arms 25 and 26 normally contacting but adapted to be held apart when the cross bar 9 is in its lowermost position by a pin 27 fixed to the arm 25 which engages with the cross bar 9.

55 The switch for controlling the upward limit

of movement of the cross bar 9 may take the form of a pair of bolts 28 slidably carried in insulating bushings 29 in the bracket 7. Springs 30 acting between the heads of the bolts 28 and the bushings 29 yieldingly hold the bolts in a downward position as adjustably limited by lock nuts 33. Fixed transversely of the cross bar 9 is a plate 34 which serves to complete the circuit through the bolts 28 when the cross bar is in its raised position. A push button 31 may be connected across the bolts 28 if desired.

Secured to the back of the frame 5 is a box 35 which contains a solenoid reversing switch indicated diagrammatically in Figure 4. The solenoid switch comprises a solenoid 36 and a plunger 37 normally held down by spring 38. Pivotally carried on the ends of an insulating cross member 39 fixed to the plunger 37 are a pair of switch shoes 39 which cooperate with switch points 43 to control the direction of rotation of the motor 20. A plate 44 fixed to the other end of the plunger 37 engages with contact points 45 to act as a holding in switch as hereinafter explained.

The various switches and solenoid are connected as illustrated in Figure 4 by leads 46 to a suitable source of current. A hand controlled snap switch 47 is provided in the circuit as shown.

A chute 48 is preferably secured to the base 6 just behind and below the cross bar 9.

In the operation of the device a valve stem 15 having external threads thereon to be tested for length and quality is slid by the operator into the groove 13 on the cross bar 9 so that the flats on the valve stem lie between and against the plates 17. The switch 47 is now thrown to start the motor 20 which rotates the hollow spindle 18 and nut 23 in a right hand or clockwise direction. The operator now lifts the cross bar 9 and thus the valve stem 15 up in the slides 8 until the nut 23 engages with the external thread on the valve stem 15. The operator can now remove his hand as the nut 23 screwing on the valve stem raises it up into the spindle and thus carries the cross bar 9 up with it.

As the cross bar 9 moves away from the base 6 the switch 24 closes as will be evident. The upward movement of the cross bar and valve stem as actuated by the screwing of the nut 23 onto the valve stem continues until the plate 34 contacts with the bolts 28. This completes the circuit to the solenoid 36 which raises the plunger 37 moving the contact shoes 40 to the upper two contact points 43, thus reversing the motor 20.

The reversing of the motor drives the nut 23 in a counter clockwise or left-hand direction so

110

that it begins to screw off the valve stem thus lowering the cross bar 9. The plate 34 will thus move away from the bolts 28, however, the plate 44 on the plunger 37 bridges the contacts 45 and 5 serves to hold the current to the solenoid 36. The downward movement of the valve stem and cross bar continues until the stem screws out of the nut 23 which allows the cross bar to drop and open the switch 24 cutting off the current to the 10 solenoid 36. As soon as the solenoid is deenergized the spring 33 will pull the plunger 37 down to again reverse the motor 20 by moving the contact shoes 40 to the two bottom sets of contacts 43.

15 The operator now inserts another valve stem into the front of the groove 13 on the cross bar 9 and thus pushes the tested valve stem out the back of the groove and onto the chute 48. The operation is now repeated as desired.

20 The motor 20 which rotates the nut 23 is relatively light and is designed to stall in case the external threads on the valve stem are improperly formed or are not of sufficient length. In case the motor stalls it will always stall when 25 the nut is screwing on the stem. In case this happens the operator may energize the solenoid 36 to reverse the motor by pushing the push button 31. If the nut 23 has bound on the valve stem and will not back off under the power of 30 the motor the operator may twist the spindle and nut with his free hand to assist the action of the motor. Of course the push button 31 may be omitted in which case the switch 47 is snapped and the valve stem removed by hand.

35 By adjusting the lock nuts 33 on the bolts 28 the length of thread tested can be varied.

40 It will be apparent that while the invention has been particularly described for the testing of external threads on valve stems that the invention can be adapted to test externally threaded articles of all sorts. Moreover, the invention 45 contemplates replacing the nut 23 and the hollow spindle 18 with an externally threaded spindle to test internally threaded articles.

45 In the embodiment of the invention described certain types of limiting switches have been specifically employed, however, it will be understood that the type or exact details of the switches may be widely varied.

50 As many other changes could be made in the construction, it is intended that all matter contained in the above description or shown in the accompanying drawings shall be interpreted as 55 illustrative only and not in a limiting sense, accordingly various modifications and applications of the invention can be resorted to without departing from the spirit of the invention or the scope of the appended claims.

What is claimed is:

1. Apparatus for testing external threads on valve stems comprising a frame, a cross bar slidably carried in said frame, a hollow spindle journaled in said frame and extending towards said cross bar, a nut on the extending end of said spindle and adapted to cooperate with the external threads on a valve stem to be tested, means for holding a valve stem on said cross bar, means for rotating said spindle, reversing means for controlling the direction of rotation of said spindle, means for automatically operating said reversing means after the nut has screwed on the valve stem a predetermined distance, and automatic means for again operating said reversing means after the nut has unscrewed from the valve stem.

2. Apparatus for testing external threads on valve stems comprising a frame, a cross bar slidably carried in said frame, a nut journaled in said frame and adapted to cooperate with the external threads on a valve stem to be tested, means for holding a valve stem on said cross bar, means for rotating said nut, reversing means for controlling the direction of rotation of said nut, means for automatically operating said reversing means after the nut has screwed on the valve stem a predetermined distance, and automatic means for again operating said reversing means after the nut has unscrewed from the valve stem. 80

3. Apparatus for testing threads on valve stems comprising a frame, a cross bar slidably carried in said frame, a threaded member journaled in said frame and adapted to cooperate with the threads on an article to be tested, means for holding an article on said cross bar, means for rotating said threaded member, reversing means for controlling the direction of rotation of said member, means for automatically operating said reversing means after said member has screwed on the article a predetermined distance, and automatic means for again operating said reversing means 95 after threaded member has unscrewed from the article. 95

4. Apparatus for testing external threads on valve stems comprising a frame, a cross bar slidably carried in said frame, a hollow spindle journaled in said frame, a nut on said spindle and adapted to cooperate with the external threads on a valve stem to be tested, means for holding a valve stem on said cross bar, weak means for rotating said spindle adapted to stall if the threads on the nut and valve stem do not conform, reversing means for controlling the direction of rotation of said spindle, means for automatically operating said reversing means after the nut has screwed on the valve stem a predetermined distance, and automatic means for again operating said reversing means after the nut has unscrewed from the valve stem. 110

5. In combination in thread testing apparatus, means for removably supporting an article to be tested, a rotatable threaded member relatively movable with respect to said article supporting means, means for rotating said threaded member, reversing means for controlling the direction of rotation of said member, means for automatically operating said reversing means upon determined relative movement of said threaded member and said article supporting means, and automatic means for again operating said reversing means after determinate opposite relative movement of 120 said article supporting means and said threaded member. 125

6. In combination in thread testing apparatus, means for removably supporting an article to be tested, a rotatable threaded member relatively movable with respect to said article supporting means, means for rotating said threaded member, reversing means for controlling the direction of rotation of said member, and means for automatically operating said reversing means upon 135 determined relative movement of said threaded member and said article supporting means.

7. Apparatus for testing external threads on valve stems comprising a frame, a cross bar slidably carried in said frame, a hollow spindle journaled in said frame and extending toward said cross bar, a nut on the extending end of said spindle and adapted to cooperate with the external threads on a valve stem to be tested, means for holding a valve stem on said cross bar, means 145

for rotating said spindle, reversing means for controlling the direction of rotation of said spindle, and means for automatically operating said reversing means after the nut has screwed on 5 the valve stem a predetermined distance.

8. In combination in thread testing apparatus, means for removably supporting an article to be tested, a rotatable threaded member relatively movable with respect to said article supporting means, means for rotating said threaded member, reversing means for controlling the direction of rotation of said member, and means for automatically operating said reversing means upon determined relative movement of said threaded member and said article supporting means, said reversing means including a reversing switch operated by a solenoid coil.

9. In combination in thread testing apparatus, means for removably supporting an article to be 20 tested, a rotatable threaded member relatively movable with respect to said article supporting means, means for rotating said threaded member, reversing means for controlling the direction of rotation of said member, means for automatically operating said reversing means upon 25 determined relative movement of said threaded member and said article supporting means, and automatic means for again operating said reversing means after determinate opposite relative movement of said article supporting means 30 and said threaded member, said reversing means including a solenoid operated reversing switch.

10. Apparatus for testing external threads on 35 valve stems comprising a frame, a cross bar slidably carried in said frame, a hollow spindle journaled in said frame and extending towards said cross bar, a nut on the extending end of said spindle and adapted to cooperate with the external threads on a valve stem to be tested, means for holding a valve stem on said cross bar, means for rotating said spindle, reversing means for controlling the direction of rotation of said spindle, means for automatically operating said reversing means after the nut has 40 screwed on the valve stem a predetermined distance, and automatic means for again operating said reversing means after the nut has unscrewed 45

50 from the valve stem, said reversing means including a solenoid operated reversing switch.

11. In apparatus for testing external thread on valve stems comprising a vertically movable slide, a rotatable nut journaled above said slide and adapted to cooperate with the external thread on the valve stem to be tested, means for holding a valve stem on said slide, means for rotating said nut, said means being relatively weak and adapted to stall if the threads to be tested do not conform to specifications, a reversing switch controlling the direction of rotation of said nut rotating means, means for automatically throwing said switch to reverse the rotation of said nut after the nut has screwed onto the stem a determined distance, and means actuated by the slide after the nut has screwed off the stem to again reverse the switch.

80 12. In apparatus for testing external thread on valve stems comprising a vertically movable slide, a rotatable nut journaled above said slide and adapted to cooperate with the external thread on the valve stem to be tested, means for holding a valve stem on said slide, means for rotating said nut, said means being relatively weak and adapted to stall if the threads to be tested do not conform to specifications, a reversing switch controlling the direction of rotation of said nut rotating means, and means for automatically throwing said switch to reverse the rotation of said nut after the nut has screwed onto the stem a determined distance.

85 13. In apparatus for testing external thread on valve stems comprising a movable slide, a rotatable nut journaled with respect to said slide and adapted to cooperate with the external thread on the valve stem to be tested, means for holding a valve stem on said slide, means for rotating said nut, said means being relatively weak and adapted to stall if the threads to be tested do not 90 conform to specifications, a reversing switch controlling the direction of rotation of said nut rotating means, and means for automatically throwing said switch to reverse the rotation of said nut after the nut has screwed onto the stem a determined distance.
